UNITED STATES PATENT OFFICE.

THOMAS B. RICE, JR., OF PHILADELPHIA, PENNSYLVANIA.

DEVICE FOR HANDLING MATERIAL.

No. 857,673.

Specification of Letters Patent.

Patented June 25, 1907.

Application filed February 14, 1907. Serial No. 357,347.

To all whom it may concern:

Be it known that I, THOMAS B. RICE, Jr., a citizen of the United States, residing in the city and county of Philadelphia, State of Pennsylvania, have invented a new and useful Device for Handling Material, of which the following is a specification:

My invention relates to a new and useful device for handling material and consists in providing a suitable support having a weight suitably connected therewith, whereby when the material is placed upon the support, by a slight pull upon the part of the operator, the said support and material will be lowered.

It further consists of other novel details of construction, all as will be hereinafter fully set forth.

In the drawings, I have shown a portion of a lock-corner machine to which my invention is attached and that when in use on this machine, it will be understood, the device is for handling boards. While I have shown the same as applied to the said machine, it will be understood that the device may be applicable and used for other purposes.

Figure 1 represents a partial sectional view and partial front elevation of a lock-corner machine showing my invention as applied thereto. Fig. 2 represents a partial sectional view and partial side elevation thereof. Fig. 3 represents in elevation, portions of the device in different positions from that seen in Fig. 2. Fig. 4 represents a partial plan view and partial sectional view of a portion of the machine showing the boards in position. Fig. 5 represents a partial plan view of a portion of the device showing the boards at one end of the support 6 about to be clamped. Fig. 6 represents a partial plan view and partial sectional view of a portion of the machine showing a few boards in position on the support 6 and showing the position of the front head 3.

Similar numerals of reference indicate corresponding parts in the figures.

Referring to the drawings:—In lock-corner machines it is to be understood that a number of boards are placed together and are fed to the saws, so that a plurality of boards are cut at one time and in practice it has been found somewhat difficult to handle the boards owing to their weight and to the quantity thereof, and I overcome this difficulty without interfering with the operation of the machine in any way.

By my device, I am enabled to quickly and easily handle the boards and while I have shown a construction for carrying out my invention, it will be understood that I do not desire to be limited in every instance to the construction as herein shown and described, as other instrumentalities may be employed which will accomplish the same results.

1 designates the base or frame of the machine having guides 2 therein in which moves the front head 3 and rear head 3^x, said heads carrying the extensions 21 and 22 respectively and being suitably connected by means of the threaded rod 23, one end of which is rotatably connected with the rear head 3^x and is in threaded engagement with a suitable opening in the front head 3, said rod having a suitable gear 24 thereon meshing with the idler 25 which is in mesh with the gear 26 which is on a shaft suitably mounted and adapted to be actuated by the hand wheel 27, it being understood that by rotating the hand wheel 27 through the medium of the gears 24, 25 and 26, the front head is caused to approach or to be moved from the rear head 3^x, this being done for the purpose of clamping the boards between the extensions 21 and 22 carried by the heads respectively, it also being understood that after the heads are separated the boards 28 are placed in position upon the support 6 with the protectors 29 and 30 at the opposite sides of the boards, after which the hand wheel 27 is suitably rotated to bring the heads 3 and 3^x together until the boards are positively locked upon the support 6 between the extensions 21 and 22 of the heads.

31 designates a gear or pinion which meshes with a rack 32 carried by the base which supports the heads 3 and 3^x. Upon power being imparted to the gear 31, it will rotate and actuate the rack 32, in order to move the heads 3 and 3^x and with them the boards 28 and support 6, so that the boards will be brought into suitable position to be cut by the saws 4 which are suitably supported and separated and carried by a suitable stationary portion of the machine.

It will be understood that Fig. 4 represents the boards locked in position and the machine just ready to be actuated so that the boards will be cut by the saws, Fig. 6 showing the position of the boards after they have been cut and the extreme position to which the head 3 moves, that is to say, it will be un-

derstood that the head 3 never passes between the saws.

5 designates tracks or guides which are movably supported on each side of the head 3^x and movable in said guides are the supports 6 which, in the present instance consists of angled bars, the lugs or extensions 7 on the guides 5 assisting in the guiding of the supports. 8 designates a cross-bar with 10 which said supports are suitably connected and carried by said cross-bar is the eye 9, which is adapted to receive a standard 10 carried by the head 3^x on the machine, whereby it will be seen that said bar 8 is properly 15 guided in its vertical movement.

Connected with the supports 6 in the present instance, by the medium of the cross-bar 8, is a cord or cable 11, which is suitably connected with the pivoted lever 12. In the 20 present instance, the cord or cable 11 passes over the pulleys 13 which are suitably supported. The lever 12 is pivoted at 14 to a suitable stationary support, said lever being provided with the movable weight 15 and is 25 adapted to contact with a stop 16 to prevent a too great depression of said lever.

17 designates an eccentrically pivoted pawl or latch which is located at a suitable point to co-operate with the bar 8 of the support 6 in the present instance, being pivoted to the track 5, the upper end of which is connected with one end of the chain or other suitable device 18, the opposite end of said chain being connected with a stationary support. In the present instance, it is connected with the rods 19, which are suitably carried by the frame 1 of the machine. The handle 20 is conveniently connected with the cross-bar 8 for imparting a pull thereon. 30 The boards 28 which are to be provided with the slots for the lock-corner are placed on the extension of the support 6, the weight 15 having been adjusted so that the boards will not immediately lower the support from its 35 upper position until the operator pulls down on the handle 20 which will thus lower the support and raise the weight 15. The boards are then locked in position as previously described and the pinion 31 actuates the rack 40 50 55 32, so that the boards are carried past the saws in order that the ends of the boards are properly cut.

It will be noted that as soon as the support 6 is lowered and the cross-bar 8 passes the latch 17, the same will be thrown, by reason of the position of its pivoted point, into engagement with said cross-bar 8, as will be best understood from Fig. 2, and that said support will be positively located in its 60 proper position and held there, it being understood that the locking of the boards between the heads 3 and 3^x also assists in properly holding the support in position. As the heads 3 and 3^x with the boards thereon move 65 to the rear of the machine, while the boards

are being passed through the saws, the weight 15 will be slightly raised, but upon the return of the parts, the weight will be in the position for assisting in raising the support and boards. After the boards, however, have assumed the position seen in Fig. 6, the movement of the pinion is reversed and the heads 3 and 3^x are returned to their former position or that seen in Fig. 2, so that the weight will be in proper position, as seen in full lines then by a slight pull upon the lever 12, the weight 15 will be lowered into the position seen in dotted lines, Fig. 2, and the support 6 will be raised. It will be understood, however, that as the boards 80 move to their rearmost position as the chain 18 is connected with the fixed rod 19 at one end and to the latch 17 at the opposite end, the upper end of the latch will be moved to the position seen in Fig. 3 by the tightening 85 of the chain 18, that is to say, the latch is automatically removed from engagement with the cross bar 8 and as the upper end of the latch with the chain attached thereto passes over the pivotal point, it will be seen 90 that the said latch will remain in the position seen in Fig. 3, while the heads 3 and 3^x and parts connected therewith return to the position seen in Fig. 2. The head 3 is now moved by the operating handle 27 so as to 95 release the boards 28 and by a slight pull on the lever 12 the weight 15 will lower and raise the support 6 together with the boards which can be easily removed and a new set of boards placed in position. As the cross bar 100 is elevated with the support 6 it will be noted that the same will strike the upper end of the lever 17 throwing the same over so that the upper end with the chain attached is upon the opposite side of the pivotal point but the 105 latch of said lever will not be in engagement with the cross bar, while the latter is elevated, but as soon as it is lowered again with another set of boards to be sawed the latch will again engage the cross bar as before. 110

Having thus described my invention, what I claim as new and desire to secure by Letters Patent, is:—

1. In a counterbalancing device for work on a traveling carriage of a machine, a support for the work capable of traveling with said carriage, means connected therewith for counterbalancing the support and the work and capable of movement to lift the work, means for holding said support in its operative position, and means operated by the movement of the carriage for releasing said means. 115

2. In a counterbalancing device for work on a traveling-carriage of a machine, a support for the work capable of traveling with said carriage, means connected therewith for counterbalancing the support and the work and capable of movement to lift the work, a latch for holding said support in its lower- 120 125 130

- most position and means operated by the movement of the carriage for releasing such latch.
3. In a counterbalancing device for work on a traveling carriage of a machine, a support for the work capable of traveling with said carriage, adjustable means connected therewith for counterbalancing the support and the work and capable of movement to lift the work, a latch for holding said support in its lowermost position and means operated by the movement of the carriage for releasing such latch.
4. In a counterbalancing device for work on a traveling carriage of a machine, a movable support, capable of traveling with the carriage, a weight in suitable connection with said support, guides for said support, means for holding said support in lowered position, and means for automatically releasing said locking means.
5. In a counterbalancing device for work on a traveling carriage of a machine, a movable support, capable of traveling with said carriage, guides therefor, a connecting rod for said support, a guide for said connecting rod, a weight suitably connected to said support capable of movement to lift the work and the support, and a pivoted latch adapted to engage said support when in lowered position.
6. In a counterbalancing device for work on a traveling carriage of a machine, a movable support, capable of traveling with the carriage, guides therefor, a connecting rod for said support, a guide for said connecting rod, a weight suitably connected to said support, a pivoted latch adapted to engage said support when in lowered position, and means for releasing said latch automatically.
7. In a counterbalancing device for work on a traveling carriage of a machine, a support, guides therefor, a connecting rod for said support, a guide for said connecting rod, a weight in suitable connection with said connecting rod and adapted to normally hold said support in elevated position, a latch adapted to engage with said support when in lowered position to hold the same, and a cord or cable connected with said latch and to a suitable stationary point for automatically releasing said latch.
